UNITED STATES PATENT OFFICE.

LOTT D. BROWN, CHAUNCEY D. FRENCH, AND FRANK MAHOOD, OF DALLAS, OREGON.

FLAX-GATHERING ATTACHMENT FOR BINDERS.

Application filed February 18, 1925. Serial No. 10,063.

To all whom it may concern:

Be it known that we, LOTT D. BROWN, CHAUNCEY D. FRENCH, and FRANK MAHOOD, citizens of the United States, residing at 5 Dallas, Polk Co., Oregon, have invented certain new and useful Improvements in Flax-Gathering Attachments for Binders, of which the following is a specification.

The present invention relates to an attachment for binders, which is adapted to be substituted in place of the usual reel and sickle bar, and has for its prime object to provide a gathering mechanism, which is especially designed for pulling flax up by the 15 root and delivering it to the binder.

Another very important object of the invention is to provide a gathering mechanism for binders, which will pull the flax up by the roots, and before delivering the 20 same to the binder will shake the dirt from the roots.

Another very important object of the invention is to provide an attachment which may be easily and readily mounted in conjunction with the binder, and will be efficient and reliable in operation, comparatively inexpensive to construct, strong, durable, not liable to readily get out of order, and otherwise well adapted to the purpose 30 for which it is designed.

With the above and numerous other objects in view, as will appear as the description proceeds, the invention resides in certain novel features of construction, and in 35 the combination and arrangement of parts, as will be hereinafter more fully described and claimed.

In the drawing:

Figure 1 is a top plan view of the attachment, showing the same associated with a 40 portion of a binder.

Figure 2 is a vertical section therethrough, taken on the line 2—2 of Figure 1, looking in the direction of the arrow.

Figure 3 is a similar section, taken on the line 3—3 of Figure 1, looking in the direction of the arrow.

Figure 4 is a detail elevation, showing the ends of the roller shafts, with the meshing gear thereon, and

Figure 5 is a similar view with the gear removed.

Referring to the drawing in detail, it will be seen that A designates generally a portion of a binder, with which this attachment 55 is to be associated.

This binder is of the conventional type, and the usual gathering reel and sickle bar are removed therefrom. Our improved gathering attachment is shown mounted on the binder, and includes a frame formed from the sides 5 and 6, the intermediate portions of which are inclined upwardly as at 7. These sides 5 and 6 are rigidly held together by cross bars 8, which are arranged as is shown to advantage in Figure 2. Shafts 9 and 10 are journaled through the inclined portions 7 of the sides 5 and 6. The shaft 9 is located above the shaft 10 and slightly forwardly thereof. A smooth roller 11 is mounted on and to rotate with the shaft 9, while a corrugated roller is mounted on to rotate with the shaft 10, and the peripheries of these rollers are disclosed in close proximity, as is indicated to advantage in Figures 2 and 3. The shafts 9 and 10 extend through the sides 5 and 6 and are journaled in blocks 13, mounted in guide rails 14, and held toward each other by springs 15, which may be tensioned by 80 screws 16. The guides 14 on one side of the attachment are mounted in a frame 17, and on the other side of the attachment in a frame 18, which is disposed adjacent the elevator of the binder. This frame 18 is 85 suitably fixed to the binder, and to the side of the attachment, as at 19, and braces 20 extend between the frame 18 and the bar 21 which is a part of the binder. On the rear end of this bar 21 an engine 22 is mounted in any suitable manner for rotating a drive pulley 23, over which is trained a belt 24, which extends under the elevator of the binder, and is further trained over a driven pulley 26 on the end of shaft 9. A gear 95 27 is keyed onto the shaft 9 and a gear 28 is keyed onto the shaft 10, and meshes with the gears 27, these gears being normally held in mesh by the springs 15 associated with journal blocks 13 in guides 14, and the 100 frames 17 and 18.

At the forward end of each side of the frame, there is provided a series of openings 30, in the form of an arch, and an arm 31 is provided with two series of longitudinally extending openings 32, which are adapted to be brought into registry with the openings 30, so that bolts 33 may be passed therethrough, for holding the arms 31, in different adjusted positions on the 105 respective side rails. At the lower ends of these arms 31, there is journaled a shaft, on 110

which is mounted a roller 34. The upper ends of the arms 31 are braced, by members 35, having a pair of sections connected by a turnbuckle 36. These members 35 are 5 attached to suitable ears 37 at the top of the inclined portions 7 of the sides 5, as is shown in Figure 2.

A belt 39 is trained over rollers 11 and 34, and may be properly tensioned by the adjustment of arms 31. The outer surface of this belt 39 is provided with a series of transversely extending cleats 40, for engagement with the corrugations of the roller 12. A guide shield 42 is hingedly mounted 10 between the ears 43, located at the bottom of the inclined portions 7 of the sides 5 and 6, and the free edge thereof is adapted to be maintained in engagement with the periphery of the corrugated roller 12, by 15 means of spring 44.

When the engine 22 is in operation, the belt 24 is caused to rotate the roller 11 and cause the travelling of the belt 39, in the direction indicated by the arrows in both 20 Figures 1 and 2. When the binder is travelling along, the under run of this belt 39 will tilt the flax toward the grain pan of the binder and cause the top thereof to engage between the belt 40 and the corrugated roller 12, whereby they will be pulled 25 up by the roots. As the roots pass over the guide shield 42, the vibration of this guide shield, because of its engagement with the corrugated roller and the spring 44 will 30 efficiently take all of the dirt from the roots, so that the flax will be delivered to the grain 35 pan of the binder, relatively clean.

It will now be apparent that we have devised an attachment particularly useful in 40 pulling up grain by the roots, and especially flax, so as to deliver the same to the grain pan of the binder, free from dirt and other foreign matter. The attachment operates to properly lead the grain, which may be engaged 45 between the belt and the corrugated roller, and this corrugated roller acts as an agitating means for the guide shield. The device possesses a comparatively simple and efficient structure, which is in no way liable to readily get out of order, and will 50 be thoroughly reliable in its operation strong, durable, and yet possessed of a relatively light construction. The obvious parts of the attachment may be quickly assembled or disassembled in relation to each other and as a whole to the binder. It will 55 further be apparent that numerous changes in the details of construction, in the materials, and in the combination and arrangement 60 of parts may be resorted to, without departing from the spirit or scope of the invention as hereinafter claimed, or sacrificing any of its advantages.

Having thus described our invention, what 65 we claim as new is:

1. In an attachment of the class described, a gathering means, an agitated guide shield associated with the gathering means for vibrating the grain gathered thereby to shake dirt from the grain. 70

2. In a gathering attachment for binders, a belt having a corrugated outer surface, a corrugated roller associated with the belt, a guide shield hingedly mounted adjacent the corrugated roller, and means for agitating the plate all in the manner and for the purpose specified. 75

3. In a gathering attachment for binders, a frame, a pair of rollers mounted in the frame, a belt trained over these rollers, a corrugated roller journaled in the frame, means for rotating the rollers, a guide plate hingedly mounted on the frame adjacent the corrugated roller, spring means for holding the free edge of the guide plate in engagement with the corrugated roller to be agitated thereby as grain is being pulled between the corrugated roller and the belt. 80

4. In a gathering attachment for binders a frame, a pair of rollers mounted in the frame, a belt trained over these rollers, a corrugated roller journaled in the frame, means for rotating the rollers, a guide plate hingedly mounted on the frame adjacent the corrugated roller, spring means for holding the free edge of the guide plate in engagement with the corrugated roller to be agitated thereby as grain is being pulled between the corrugated roller and the belt, and means for mounting the attachment on 90 a binder for delivering the grain pulled thereby onto the grain pan of the binder. 95

5. In a gathering attachment of the class described adapted for use with binders, a frame, a roller at the forward end of the frame, a second roller at the rear end of the frame, a third roller at the rear end of the frame below the second roller and slightly to the rear thereof and provided with a corrugated periphery, a belt trained over the first and second rollers and provided on its outer surface with transversely extending cleats, shafts for the second and third rollers, journal blocks for the shafts, resilient means associated with the journal blocks for holding the second and third rollers in close proximity to each other, guides on the frame for the blocks, a guide shield hingedly mounted on the frame and having its free end normally engaged with the corrugated roller, spring means for normally holding the free edge of the guide shield in engagement with the corrugated roller, means for rotating the rollers for travelling the belt and agitating the guide shield. 110

6. In a gathering attachment of the class described adapted for use with binders, a frame, a roller at the forward end of the frame, a second roller at the rear end of the frame, a third roller at the rear end of the frame, a guide shield hingedly mounted on the frame and having its free end normally engaged with the corrugated roller, spring means for normally holding the free edge of the guide shield in engagement with the corrugated roller, means for rotating the rollers for travelling the belt and agitating the guide shield. 115

frame below the second roller and slightly to the rear thereof and provided with a corrugated periphery, a belt trained over the first and second rollers and provided on its outer surface with transversely extending cleats, shafts for the second and third rollers in close proximity to each other, guides 30 on the frame for the blocks, a guide shield hingedly mounted on the frame and having its free end normally engaged with the corrugated roller, spring means for normally holding the free edge of the guide shield 35 in engagement with the corrugated roller, means for rotating the rollers for travelling the belt and agitating the guide shield, a shaft for the first roller, arms for said shaft, said frame provided with a plurality of 40 openings, said arms being provided with a plurality of openings, bolts insertable through said openings to hold said arms in different adjusted positions upon the frame.

10 proximity to each other, guides on the frame for the blocks, a guide shield hingedly mounted on the frame and having its free end normally in engagement with the corrugated roller, means for rotating the rollers

15 for travelling the belt and agitating the guide shield, a shaft for the first roller, arms for said shaft, and means for adjustably supporting said arms on the frame.

7. In a gathering attachment of the class 20 described adapted for use with binders, a frame, a roller at the forward end of the frame, a second roller at the rear end of the frame, a third roller at the rear end of the frame below the second roller and slightly 25 to the rear thereof and provided with a cor-

rugated periphery, a belt trained over the first and second rollers and provided on its outer surface with transversely extending cleats, shafts for the second and third rollers in close proximity to each other, guides 30 on the frame for the blocks, a guide shield hingedly mounted on the frame and having its free end normally engaged with the corrugated roller, spring means for normally holding the free edge of the guide shield 35 in engagement with the corrugated roller, means for rotating the rollers for travelling the belt and agitating the guide shield, a shaft for the first roller, arms for said shaft, said frame provided with a plurality of 40 openings, said arms being provided with a plurality of openings, bolts insertable through said openings to hold said arms in different adjusted positions upon the frame.

In testimony whereof we affix our sig- 45 natures.
